UNITED STATES PATENT OFFICE

JOHN M. SHIELDS, OF CHICAGO, ILLINOIS, ASSIGNOR TO F. H. NOBLE & COMPANY, OF CHICAGO, ILLINOIS, A CORPORATION OF ILLINOIS

DISPLAY PAD FOR WRIST WATCH BOXES

Application filed May 4, 1932. Serial No. 609,092.

My invention relates to small boxes, usually more or less ornamental in design and finish, which are used as containers for the reception and display of wrist watches 5 equipped with a band of leather, or similar material, and more particularly relates to the display pad member of the article. Display pads for such boxes are well known in which the watch is displayed centrally of 10 the face of the pad and in which the strap members extend laterally around the opposite ends of the pad and are buckled, or otherwise secured together, usually rather tightly, on the under side of the pad, but it 15 has been found by experience that when a wrist watch and strap remains on display on such a pad for a considerable time, the leather strap members receive a somewhat permanent set at the bends where they extend around the ends of the pad, and this 20 has proved objectionable. One object of my invention is to provide a display pad of such construction that there is no necessity for buckling the strap ends together, con- 25 ducing to the defect mentioned; another is to produce a pad of sightly appearance displaying only the watch (or other article) and short strap sections only on each side thereof; and other objects are the attain- 30 ment of these advantages by a simple and desirable arrangement of separable members of a display pad structure of composite two- part construction.

With these objects and advantages in 35 view, I have designed and invented the display pad for a wrist watch box hereinafter described in detail, the essential elements of my invention being more particularly pointed out in the appended claims.

40 Figure 1 of the drawing is a perspective of a box with the lid raised, showing a display pad therein embodying my invention;

Fig. 2 is a perspective of the upper member of the pad;

45 Fig. 3 is a perspective of the lower pad member;

Fig. 4 is a longitudinal central vertical section of the box, the contained wrist watch and strap being shown in elevation; 50 and

Fig. 5 is a top plan view of a modified form of my invention.

Like reference characters indicate like parts on all the figures of the drawing.

It will be understood that the box body 1 and lid or cover member 2 may be of any desired or suitable construction adapted to receive the display pad to which my invention particularly relates. This pad is of double or two-part construction, and includes a bottom section 3 and an upper, display section 4, both formed of sheet metal and covered with ornamental facings to provide a finished appearance. The display field formed by the top of the upper display section of the pad, in the present instance, though not necessarily, comprises a broad forwardly and downwardly sloping trapezoidal face 6, a narrower rear trapezoidal face 7, and triangular end faces 8 and 9, all connected to a marginal rectangular downwardly extending flange 10. The bottom section 3 is provided at its ends with upwardly extending curved tongues 11 which match with and are approximately complementary to inwardly extending notches 12 formed in the ends of the upper member, the proportions being such that a slight strap-receiving gap is provided between the end of each tongue 11 and the proximate edge 80 of the notch which receives it. The bottom section is also provided with tongues 13 arranged to frictionally engage the flange 10 of the upper member of the pad. The outer face of each tongue 11 of the lower section is 85 covered with a facing 14 of an ornamental material, such as plush or velvet, which preferably, and as illustrated, extends around the edges to the opposite inner face, and the display field of the lower section 4 and outer edges of the flange 10 are covered with the same material, marked 15, so that when the parts are assembled as shown in Fig. 1, with the watch disposed on the forward face 6 of the upper member, and the strap ends ex- 90 tending downwardly through the gaps at the ends of the notches 12, the upper faces of the pad, or display field, will present a continuous appearance. If desired, and as illustrated, the upper side of the bottom sec- 100

tion 3 may be finished with a facing of paper or fabric 16, and the lower side of the section 4 with a similar facing 17, concealing the raw edges of the facing material 14 or 5 15.

It will be observed that the gaps or strap-receiving opening between the ends of the tongues 11 and the bottoms of the notches 12 permit the perforated and buckle-carrying 10 strap members marked 18 and 19 respectively, of the watch to pass therethrough somewhat loosely and without constraint into the space below the pad, and that it is unnecessary to buckle the strap and draw it more 15 or less tightly upon the pad member. It will be noticed, also, that only comparatively short sections of the strap on opposite sides of the watch are displayed, the frame or field of the facing material of the pad extending 20 entirely around the watch and visible portions of the strap members, thus presenting a unique and pleasing appearance.

In Fig. 5 I have illustrated a modification of my invention in which one end only 25 of the upper section of the display pad, marked 4^a, is formed with a notch, marked 12^a, and a single tongue 11^a is formed on the bottom section 3^a, an orifice or strap-receiving opening marked 20, being formed 30 opposite the gap at the end of the notch 12^a to receive the perforated strap member of the watch. This permits the perforated strap end to be threaded through the orifice 20, while the strap member equipped with 35 the buckle is carried into the notch 12^a whilst the upper and lower members are separated, the parts of the pad being then assembled as in the form of my invention hereinbefore described.

40 While my invention is particularly suited for use in the construction of small ornamental boxes intended for the display and safe-keeping of wrist watches, it may be similarly employed in connection with the 45 display of other articles provided with strap members, as certain kinds of emblems, badges, lockets, garters, arm-bands, etc., and I desire the appended claims construed to cover such uses and all mechanical equivalents for the elements specifically recited. 50

I claim:

1. In a container for wrist watches and the like, a display pad comprising an upper section having a display field, said section being formed at at least one end with an inwardly-extending notch, and a lower section provided with an upwardly extending end tongue matching said notch and providing between the ends of the tongue and notch a strap-receiving gap. 55

2. In a container for wrist watches and the like, a display pad comprising an upper section having a display field, said section being formed at its opposite ends with inwardly-extending notches, and a lower sec- 60

tion provided at its opposite ends with tongues matching said notches and providing between the ends of the tongues and corresponding notches a pair of strap-receiving gaps. 70

3. In a container for wrist watches and the like, a display pad comprising an upper section having a display field, said section being formed at one end with an inwardly extending notch and adjacent the other end being formed with a strap-receiving orifice, and a lower section provided with a tongue matching said notch and providing between the ends of the tongue and notch a strap-receiving gap. 75

4. In a container for wrist watches and the like, a display pad comprising separable upper and lower sections, said upper section having a display field and being formed with a marginal depending flange and a notch extending from at least one end inwardly through said flange towards the center of said display field, and said lower section being detachably connected to said upper section adjacent the lower edge of 80 said flange and being formed with an upwardly extending end tongue matching said notch and providing between the ends of the tongue and notch a strap-receiving gap. 85

5. A display pad for wrist watch containers according to claim 4 in which the exposed faces of upper and lower sections are provided with like ornamental facings, whereby a continuous display field is provided surrounding a displayed wrist watch 90 and visible portions of the strap members thereof. 95

6. In a container for wrist watches and the like, a display pad comprising separable upper and lower sections, said upper section having a display field and being formed with a depending marginal flange and at its opposite ends formed with notches extending inwardly through said flange towards the center of said display field, and said lower section being detachably connected to said upper section adjacent the lower edge of said flange and being formed with a pair of opposite upwardly extending, inwardly bent end tongues severally matching said notches of the upper section and providing strap-receiving gaps at opposite sides of the center of said display field. 100 105 110 115 120

In testimony whereof, I have subscribed my name.

JOHN M. SHIELDS.
